ELECTRIC MERCURY TUBE SWITCH

Ira E. McCabe, Chicago, Ill.

Application December 31, 1928, Serial No. 329,548

2 Claims. (Cl. 200—152)

- This invention relates to the manufacture of electric mercury tube switches, and more particularly to mercury tube switches with both electrodes projecting from one end.
- 5 It is an object of this invention to manufacture mercury tube switches by machinery in a way that will not only lessen the number of operations it has heretofore necessitated by hand, but also increase the uniformity of the product.
- 10 It is another object of this invention to provide a construction of switch tube in which a blown bulb may be employed in place of shaping a piece of glass tubing for this purpose. Bulbs blown in a mold are much more uniform than heating and closing one end of a tube by hand.
- 15 It is also an object of this invention to provide a filling stem in the sealed end of the bulb that also supports the leading in wires of the electrodes and provide means in connection with the exterior projection of the filling stem for supporting and reinforcing the connections of the lead wires to the electrodes and the exterior lines.
- 20 With these and other objects in view, reference is made to the accompanying sheets of drawings which illustrate preferred forms of this invention; it being understood that minor detail departure may be made therefrom without departing from the scope of this invention.
- 25 In the drawings:
- 30 Figure 1 is a view in central horizontal section of the switch bulb supported above the support holding the leading in wires attached to their respective electrodes and the filling stem, before the bulb is heated and the heated portion pinched to embrace the same.
- 35 Figure 2 is a similar view of the bulb, leading in wires carrying the electrodes, and the filling stem, after the open end of the bulb has been heated and the side walls pressed together to form an end seal, engaging and supporting the wires and tube.
- 40 Figure 3 is a view similar to Figure 2, illustrating the filling stem tipped and sealed off.
- 45 Figure 4 is a view similar to Figure 3 showing the leading in wires connected to the lead wires or exterior line and one means for supporting and reinforcing these connections.
- 50 Figure 5 is a view in side elevation of Figure 4.
- 55 Figure 6 is a view in central horizontal section, partly in elevation, illustrating another means for supporting and reinforcing the switch connections.
- Figure 7 is a similar view of another type of switch connection.
- Figure 8 is a view in end elevation of Figure 7.
- Figure 9 is a view similar to Figure 7 illustrating another type of switch connection.
- Figure 10 is a view in side elevation of Figure 9.
- Figure 11 is a top plan view of Figure 6.
- Mercury tube switches of various types have long been used in electric circuits for various purposes. Of late years they have been extensively used in control devices such as employed in domestic refrigerating machines, electric flashing signs, domestic oil burner systems and the like. 5 Such mercury tube switches usually comprise an elongated cylindrical glass container closed at both ends, into which the electrodes of the circuit to be controlled project, usually adjacent to each other and either through a side wall adjacent a closed end or through a closed end, the air exhausted from the container and a body of mercury and an inert gas inserted, the body of mercury being sufficient when the container or tube is tilted toward one end, the mercury flowing to that end closes the circuit between the electrodes, and when tilted in the opposite direction, the mercury flows away from the electrodes and opens the circuit therebetween. The containers were usually formed from sections of glass 10 tubing heated and closed by hand, and more recently the electrodes have been supported in a machine, an open end of the same tube supported over the electrode, heated and the sides pressed together to close that end and seal the electrodes 15 therein at the same time, while the other end has been manipulated by hand to be first drawn to a small tube through which the air could be exhausted and the mercury and inert gas inserted, then the tube was tipped and sealed off to close 20 that end.
- The present invention contemplates the employment of bulbs blown in a mold having cylindrical sides and a right angular closed end, such as the bulb illustrated in Figure 1, which insures 25 uniform dimensions. The electrodes (2) are each formed of a metal that will not amalgamate with the mercury within the tube when the circuit is made and broken thereby, and are preferably welded to leading in wires (3) which are of such 30 a character as will form a seal with the walls of the tube, which is usual construction. The bulb (1) is grasped in movable jaws (1a) and the leading in wires (3) are positioned in proper relation in a stationary block (1b) of a machine 35 which includes means for heating the walls of the bulb about the open end until plastic, and while the walls of the bulb are plastic, pinching them together about the leading in wires, forming a flat projecting end closure (4) as shown 40

in Figures 2 and 4, all of which machinery is of known construction in the glass manipulating art.

This invention contemplates further the provision of a filling stem (5) in the form of a small glass tube and means for supporting the same in the block (1b) in line with and intermediate the leading in wires (3) with its end projecting a sufficient distance above the surface of the block 10 to communicate with the interior of the bulb (1) after the plastic open end has been closed about the sealing in wires and projecting tube. To prevent the heated plastic end walls from closing the base of the filling stem (5), a wire (6) is inserted therein as shown in Figure 1 during the pinching of the end seal. If desired the wire 15 may be a tube and air may be blown through same to shape the bulb properly after pressing, or air may be blown through the hole made by 20 the solid wire after same is removed. The manner in which this is accomplished is disclosed in Letters Patent No. 1,872,070, granted Ira E. McCabe and Karl Hunciker August 16, 1932 and in the application of Karl Hunciker, Serial No. 25 393,389, allowed July 21, 1932 and assigned to Ira E. McCabe. The closed bulb is then removed from the machine as shown in Figure 2, and the air removed from the interior and the desired amount of mercury and the desired inert gas admitted through the filling stem (5) and the stem 30 tipped and sealed off adjacent the body of the seal (4) leaving a projecting tip (1).

Lead wires (8) preferably formed of fine tubular beaded wires having the usual insulation, are 35 then forced over each extending leading in wire (3), as shown in Figure 4, a band or flat ring of insulating material (9) is then slid down over the lead wires (8) until it engages the end of the glass seal, which band or ring snugly fits over 40 and holds together the joints of the lead wires (8) with the leading in wires (3), forming a joint in accordance with the prior patent No. 1,840,869, granted R. W. Armstrong and Ira E. McCabe 45 August 30, 1927, although any other usual forming connection may be employed. Another band or flat ring (9) of insulating material is then snugly placed about the outside of the ends of the covered joints of the lead wires which insulation also embraces the exterior of the end 50 closure (4). It is to be noted that the leading in wires (3) and tip (1) of the filling stem are positioned in such relation that the insulated ends of the lead wires (8) bear against the tip (1), and when the surrounding band (9) is in 55 place, the joints are supported and reinforced so that pulls or tugs on the lead wires (8) out of line with the leading in wires (3), are resisted by the band (9), preventing injury to these joints so surrounded.

60 While the form just described is a preferred form of supporting and reinforcing the lead and leading in wire joints, the same may be accomplished in other ways to bind the joints to the rigid projecting tip (1) without departing from 65 the scope of this invention. Other forms for accomplishing the result contemplated are illustrated in Figures 6 to 11, inclusive.

In Figure 6 the lead wires (8) extend in prolongation of the wires 3. In Figure 7 the lead 70 wires (8) are bent parallel to each other and at right angles to the plane passing through the

wires 3. In Figure 9 the lead wires (8) are bent away from each other in the plane passing through the wires 3.

While the insulating tubular band 9 makes a satisfactory binding and reinforcing support it 5 would be difficult to apply to the types shown in Figures 7 and 8. Since this invention contemplates means for supporting and reinforcing the switch connections, a non-conducting plastic substance 10 may be worked about and between 10 the joints of the lead wires, filling stem and sealed end of the tube 1, which will afterwards harden and support and reinforce the joints. Sealing wax, bakelite, or any non-conducting cementitious material may be employed for this 15 purpose, and should not only surround the lead wire joints and tipped end of the filling stem but should also embrace the sealed end of the tube and completely cover the tip of the filling tube, as shown in Figures 8, 10 and 11. 20

Before the blown bulbs 1 were employed in switches of this character, it was customary to draw one end of a tube to form a filling stem, even after the electrodes were sealed in one end, as shown herein. Then after the air had been 25 removed and the mercury and inert gas passed through the filling tube, the said tube was sealed or tipped off leaving a short projection extending from that end of the tube. Such a projecting tip was a source of weakness inasmuch as in 30 handling the tip became broken and the tube inoperative.

This novel arrangement of the filling tube between the electrodes and lead wires makes a structure which protects the tip of the filling 35 stem and by surrounding and engaging both the lead wires and tip of the filling stem a much more durable mercury tube switch is produced.

What I claim is:

1. An electric mercury tube switch including 40 a cylindrical container having a tipless closure at one end and having projecting electrodes and an interposed filling stem sealed in the other end with flexible lead wires attached to the projecting electrodes on each side of the filling stem, and 45 means securing the electrodes with the attached flexible lead wires to the rigid filling stem, whereby the lead wires may be flexed without imparting movement or strain to the projecting electrodes. 50

2. An electric mercury tube switch including 55 a cylindrical container having a tipless closure at one end and having a projecting filling stem with electrodes projecting on each side thereof sealed in the other end with flexible lead wires surrounding and attached to the projecting electrodes throughout the external portions thereof and filling in the space between the electrodes and stem, the end of the filling stem tipped in line with the exterior terminations of the respective electrodes, and a band of protective material surrounding the electrodes with the attached flexible leads, interposed rigid filling stem and end of the tube seal to bind the attached portions of the flexible leads to the electrodes 65 and to the rigid filling stem, to cover and to protect the attaching means and to impart rigidity to the parts projecting from the sealed end of the tube. 60

IRA E. McCABE. 70
